UNITED STATES PATENT OFFICE.

ALBERT WILDEN, OF COLOGNE, GERMANY.

TYPING APPARATUS FOR LABELS.

Application filed September 9, 1921. Serial No. 499,582.

To all whom it may concern:

Be it known that I, ALBERT WILDEN, a German subject, residing at Cologne, in the Rhine Province, Germany, have invented 5 new and useful Improvements in Typing Apparatus for Labels (for which I have filed applications in Germany, No. 291,273, filed 3 October, 1914; Germany, No. 340,709, filed 25 July, 1918; Italy, No. Reg. 291,1,542, 10 filed 24 May, 1920; Switzerland, No. 86,388, filed 31 December, 1919; France, No. 509,034, filed 6 January, 1920; Belgium, No. 284,084, filed 29 December, 1919; Austria, No. 85,238, filed 17 December, 1919; England, No. 27,759/19, filed 10 November, 1919; Spain, No. 75,791, filed 30 September, 1920; Portugal, No. 11,865, filed 2 October, 1920; Denmark, No. 3,043, filed 27 September, 15 20 25 30 35 40 45 50 55 60 65 70 75 80 85 90 95 100 105 110 Norway, No. 21,893, filed 29 September, 1920), of which the following is a specification.

This invention relates to typing apparatus for labels, and is of that kind in which the impression is effected by a vertically moving type-box furnished with exchangeable type. Existing apparatus have the objection that for change of type in printing it is necessary to introduce a fresh set of type from a suitable store, so that the use of such apparatus is expensive in material and in time wasted.

It is my object, first, to provide a compact apparatus for the purpose which contains a plurality of slidable type carriers of 35 select types for immediate printing; and, second, to provide said apparatus with a simple device for spacing and adjusting the length of labels.

In the following description of an apparatus embodying the above features, reference 40 will be had to the accompanying drawings, in which:—

Figure 1 is a side elevation, partly in section, of the complete apparatus; Fig. 2, 45 a longitudinal section and Fig. 3, a plan of the type carrier; while Fig. 4 shows a side view of the device for altering the spacing.

The vertically movable typebox contains, according to the example shown on the 50 drawings, six type carriers 1 which can be slid parallel along the box 2 on guides 3 fixed on the bottom plate 4, each carrier being fitted with a headbutton 5 by which it can be pushed along. As shown in Figs. 2 55 and 3, each type carrier is arranged at one side for large type and at the other end

for small type of which latter there are two rows for one row of the large type. The bottom plate 4 of the box 2 has an aperture 6 equal to the largest printing surface through which the type 7 descends. Thus, by shifting any type carrier to one or other side small or large type is brought over the aperture 6 for the desired impression on the label. The box 2 has a 60 cover 8 formed with an aperture corresponding to the lower aperture 6, and with slots 9 at the left hand portion for the passage of the stems and heads 5 of the carriers 1. For securing the type carriers in the required position, the spring-pushed stems and heads 5 have a nose which can be lifted through the vertical slots 10 in the slotted cover 8 and then snap into another slot 10 65 70 75 for stopping the carrier. To keep the type down during impression, a spindle 17 is screwed down upon a hinged plate 18 placed over the type in actual use. The spindle 17 is fitted in a hinged bow 19 so arranged as to be thrown back after the release of a 80 spring catch 20, then allowing of the lifting of the cover 18 and giving access to the type. The vertical lift of the typebox, whose up and down motion is guided by stems 11 lodged in sockets 12, is effected by 85 means of a crankshaft 13 and cam 14. The latter is such as to impart to the typebox a quick lift after an impression and then keep the box elevated until the unfinished label 15 has been suitably advanced in the manner 90 and by the means hereinafter described. Meanwhile an inkribbon has advanced in the usual manner and when now the tensioned springs 16 pull down the typebox there will be produced a fresh impression 95

on the label portion situated on the platen 36. By causing the springs to pull down the typebox, instead of lifting same as in previous arrangements, the different thicknesses of label-material are compensated for 100 automatically, while moreover an elastic stroke is obtained for typing thus ensuring for perfect and clear impressions. Instead of an ink-ribbon, other inking means may be adopted.

The proper forward spacing of the strip 15 for the label is effected as follows: When the typebox is elevated, a cam 21 on the shaft 13 depresses the lever 22 which by means of a link 23 pulls round a spring-controlled 110 arm 24 carrying a pawl 25, said arm turning on a fixed shaft 26. The pawl 25 then

turns the ratchet wheel 27 and a toothed wheel 28 fast thereto. The toothed wheel turns a smaller wheel 29 controlling the spacing roller 30 with its pressure roller 31 and so advances the strip 15.

In the constructional example here shown, the cam 21 can only impart an invariable stroke to the lever 22. In order to provide variation of spacing, a lost motion is adopted 10 which renders a variable portion of the lever stroke inoperative. The loose ratchet 27 is close to a loose disc 32 on the shaft 26, said disc having an overhanging rim encircling the periphery of the ratchet 27. The rim 15 of the disc 32 is cut out for a suitable portion to expose the ratchet and ensure to the pawl 25 the maximum of spacing action; this being equal to a complete revolution of the rollers 30 and 31. To alter the spacing, 20 the disc 32 is turned by means of a pointer 34 fast thereon and moving over a scale 35 so as to cause the pawl 25 to slip over the disc 32 for any desired portion of lever-stroke before engaging the ratchet 27. This 25 then enables the turn of the ratchet and the

spacing of the strip 15 to be varied. The severing of a label is automatically effected by a knife 37 fixed to the box 2 above the platen, whereby the printed label is cut off at the printing of another label.

30

I claim:

1. A typing apparatus for labels, consisting of a typebox, slidable type carriers within same, means for guiding, shifting and stopping said carriers in position in an aperture of the typebox, a platen beneath the aperture, mechanism for lifting the box, and springs for pulling same to make the impressions.

2. A typing apparatus for labels, consisting of a typebox, slidable type carriers, each loaded with large and small type, within the box, means for positioning the type selected for an impression, resilient means for performing the impression, means for holding down the butts of the type for an impression, lifting means for the typebox, and a variable-stroke device for the forward spacing of a label-strip.

ALBERT WILDEN.
